UNITED STATES PATENT OFFICE.

JACOB MÜLLER, JR., OF NEW YORK, N. Y., ASSIGNOR TO CAROLINE H. MÜLLER,
OF NEW YORK, N. Y.

ROTARY BARREL-SPRINKLING MACHINE.

No. 911,320.

Specification of Letters Patent.

Patented Feb. 2, 1909.

Application filed May 23, 1908. Serial No. 434,629.

To all whom it may concern:

Be it known that I, JACOB MÜLLER, Jr., a citizen of the United States of America, residing at New York, in the borough of the Bronx, county and State of New York, have invented certain new and useful Improvements in Rotary Barrel-Sprinkling Machines, of which the following is a specification.

10 This invention relates to an improved rotary barrel-sprinkling machine of that type in which a number of barrel-supports are rotated by a worm-gear transmission from a suitable driving shaft on a stationary platform, and in which simultaneously the sprinkler-nozzles, located in each barrel-support, are rotated on their axes by pinions at their lower ends which mesh with a stationary gear-wheel. The hot and cold water 15 is supplied to the sprinkler-nozzles by a central distributing valve and radial connecting pipes, while the waste water is conducted by suitable pipes from the barrel-supports to a circular gutter and then to the waste-pipe. 20 The objections to this class of barrel-sprinkling machines consists mainly in the unsatisfactory working of the central distributing valve for the reason that when the same is adjusted too tightly in its casing the working 25 of the machine is impeded and sometimes entirely stopped, while when the distributing valve is adjusted too loosely in its casing, an annoying leakage and loss of hot and cold water, required for the sprinkling operation 30 takes place.

The object of this invention is to supply an improved construction of distributing valve for the hot and cold water, which when properly adjusted works in a very reliable and effective manner, without either retarding or stopping the motion of the sprinkling machine or causing the leakage of the valve when the same is either set too tightly or too loosely; and for this purpose 40 the invention consists in an improved construction of the distributing valve for rotary barrel-sprinkling machines of the horizontal type, which valve-construction will be fully described hereinafter and finally 45 pointed out in the claims.

In the accompanying drawings, Figure 1

represents a perspective view of my improved rotary barrel - sprinkling machine, Fig. 2 is a side elevation, partly in vertical central section, drawn on a larger scale, 55 Fig. 3 is a detail vertical central section through the central distributing valve, Fig. 4 is a diagram showing the arrangement of the inlet and outlet channels for the hot and cold water-supply and the points of putting 60 on and taking off the barrel, Fig. 5 is a detail vertical central section of the rotary main-portion of the distributing valve, Fig. 6 is a plan-view of the same, Fig. 7 is a top-view of the upper portion of the distributing 65 valve, Fig. 8 is a vertical transverse section of the same on line 8, 8, Fig. 9 is a top-view of the lower portion of the distributing valve, Fig. 10 is a side-view of the same, Fig. 11 is a top view of the intermediate disk-portion of the distributing valve, located between the main-portion and lower portion; and Fig. 12 is a side-view of Fig. 11.

Similar letters of reference indicate corresponding parts throughout the several figures.

Referring to the drawings, *a* represents a circular gutter the inner circumference of which is provided with inwardly-projecting brackets *a*¹ to which are attached radial 80 channel-bars *a*², said channel-bars forming a cross-shaped stiffening frame for the gutter *a*. At the center of the channel-bar frame *a*² is supported a water-collecting pan *b*, which is attached to the channel-bars by 85 suitable bolts *b*¹, and to which is attached the lower portion of the central distributing valve *v*. From the approximately-cylindrical main-portion *v*¹ of the distributing valve *v* extend radial and somewhat upwardly-inclined water supply-pipes *d* which communicate with the lower parts of cup-shaped barrel-supports *e* the upper edges of which are made concave or arc-shaped so as to support the barrels placed in position 90 thereon. The shanks of the barrel-supports *e* are supported equidistantly from each other on a ring-shaped frame *e*¹, which moves on rollers *r*, the shafts of which are supported in bearings *r*¹ and hangers *r*² below the barrel-supports, over a circular rail *r*³ at the inner circumference of the gutter *a*, said roll- 100

ers being located at the inside of the ring-shaped frame e^1 , as shown clearly in section on the left hand side of Fig. 2. To the outer circumference of the ring-shaped frame e^1 is applied a worm-gear-wheel e^2 which intermeshes with a worm w that is located on the driving shaft s , said driving shaft being supported in bearings of suitable standards located near the point where the barrels are placed on the barrel-supports. The worm w receives rotary motion by a suitable belt-and-pulley transmission from an overhead shaft or from an electric or other motor placed directly on the shaft s .

In each barrel-support is arranged a central vertical sprinkler-pipe n , the slotted or perforated upper end or nozzle of which projects slightly above the barrel-support, and the middle portion of which is supported in a stuffing-box n^1 located at the upper end of the elongated hub n^2 of the barrel-support. The lower portion of the sprinkler-pipe is slotted and connected with the outer end of the radial water-supply pipe d , while the downwardly extending shaft-portion n^3 of the sprinkler-pipe n passes through a second stuffing-box n^4 at the lower end of the sprinkler-pipe supporting hub n^2 , and is provided with a pinion p which meshes with a rack p^1 that is located at the outer circumference of the inner wall of the gutter, adjacent to the track-rail r^3 for the rollers r . The pinions p are moved in planetary motion around the gear-wheel p^1 by the motion imparted to the ring-shaped frame e^1 by the worm and worm-gear transmission, and transmit thereby rotary motion to the sprinkler-pipes on their axes so as to distribute the water ejected by the nozzles of the same in the usual manner over the interior of the barrels for sprinkling and cleaning the interior of the same.

The machine so far described is well known and for the most part described in Letters Patent No. 881,575, dated March 10, 1908. The improved feature consists in the construction of the central distributing valve v . This valve consists of four portions: a main-portion v^1 which is connected by four radial channels v^2 with the radial water-supply pipes d , an upper portion v^3 of the disk-shape which is provided with two interiorly-threaded sockets v^6 for the hot water and cold water supply-pipes f , f^1 , a lower portion v^4 which is provided with outlet-channels o^1 for the water, and an intermediate disk-shaped portion v^6 which is interposed between the bottom of the main portion and the lower or base-portion v^4 . The main portion v^1 is rotated on its axis by the motion imparted to the ring-shaped frame e^1 and the barrel-supports by the worm gear transmission, while the upper portion and the lower and intermediate portions are supported in stationary position at the center of

the channel-bar frame a^2 by a center-post g which is splined to the upper portion v^3 and the lower and intermediate portions v^4 , v^6 , as shown clearly in Fig. 3. The main-portion v^1 turns by its central opening on the center-post g , the opening being large enough for preventing any friction of the main-portion with the center-post. Into the upper end of the center-post g is inserted a screw-bolt g^1 of smaller diameter, which is threaded at its upper and lower ends and provided with a shouldered collar g^2 , between which and the part v^3 is interposed a helical spring g^3 , of considerable strength, which is compressed by a screw-nut g^4 that is applied to the upper threaded end of the post g^1 so as to regulate the pressure of the spring on the upper portion v^3 and hold the latter, as well as the intermediate and lower portions, tightly in contact with the main-portion v^1 . The parts v^3 and v^6 are preferably made of composition metal for the purpose of resisting wear between them and the rotating part v^1 ; and the latter part is provided at its upper and lower ends with recesses into which the parts v^3 , v^6 fit snugly in order to form a water-tight connection. The parts v^4 , v^6 are made separate from each other, so that the whole lower part of the valve does not have to be made out of composition metal, and also for the reason that the wear-resisting part v^6 can be replaced when worn out without requiring an entire new bottom-part for the valve. All the portions of the valve v are provided with central openings for the center-post g and the portions v^3 , v^4 and v^6 with grooves for the splines connecting them with the center-post g . The main-portion v^1 is further provided with the four radial channels v^2 which have T-shaped inner ends, the upper ends of which channels are connected with segmental channels v^8 at the underside of the upper portion v^3 , which channels communicate with the hot and cold water-supply pipes f , f^1 , while the lower ends of the T-shaped channels communicate with outlet-ports o in the intermediate portion v^6 and o^1 in the lower portion v^4 through which ports the waste hot and cold water remaining in the pipes is drained off into the collecting pan b and from the same by a connecting pipe to the circular gutter a . The outlet-ports o^1 are formed simply in the upper flange of the base-piece v^4 , as shown in Fig. 10, and do not extend downwardly entirely through the same, so that the water after passing through the upper flange passes down at the outer face of the middle part of the base-piece v^4 into the collecting pan, which is immediately below the latter. The outer ends of the T-shaped channels communicate with the radial water supply-pipes d . The water collected in the barrel supports after sprinkling the barrels, is drawn off by drain-pipes e^3 into the gutter a .

When the ring-shaped frame with the barrel supports and radial supply-pipes is rotated by the worm gear transmission, the main-portion of the distributing valve is 5 also rotated with the same around the center-post. When a barrel is placed on the first barrel-support, the rotation of the middle portion of the valve produces the supply of hot water from the hot-water pipe 10 through the T-shaped channel and its water supply-pipe to the axially-rotating sprinkler-pipe, so that a supply of hot water is conducted to the interior of the barrel on the support for the distance shown in the 15 diagram, Fig. 4, until the upper end of the T-shaped channel in the main-portion has passed the segmental channel in the upper portion and cuts off the water-supply. By the continuation of the rotation of the middle portion of the distributing valve, the hot 20 water in the radial supply-pipe is drawn off through the outlet-ports in the intermediate and lower portions of the valve and drained off into the collecting pan *b* and from there 25 to the circular gutter. By the continuation of the rotary motion of the main-portion, the second segmental channel at the under-side of the upper portion of the valve is placed in communication with the upper end 30 of the T-shaped channel of the main-portion and in connection with the cold water supply-pipe, so that cold water is supplied from the distributing valve to the sprinkler-pipe of the barrel-support and the barrel washed 35 out with cold water, while, as soon as the end of the segmental channel is passed, the cold water is cut off, the cold water in the barrel being then drained off through the channels and ports of the main, intermediate 40 and lower portions into the collecting pan and gutter, until the barrel-support arrives at the point where the barrel is taken off, at which point the cleaned barrel is removed and a new barrel placed in position 45 on the barrel-support, as the same moves forward to the putting-on point, as shown in the diagram, Fig. 4. As there are four barrel-supports, four barrels are successively sprinkled with hot and cold water 50 during each full rotation of the ring-shaped supporting frame, the cleaned barrels being removed at the take-off point and new barrels placed on the barrel-supports as they arrive successively at the putting-on point 55 for the new barrel. In this manner an intermittent sprinkling and washing of the interior of the barrels with hot and cold water is obtained, the machine requiring only one attendant who puts the barrels to 60 be cleaned on the barrel-supports and removes the washed barrels at the taking-off point. Each barrel passes successively first, through a sprinkling with hot water, then through a period of draining off the hot 65 water, then through a sprinkling with cold

water, and then through a period of draining off the cold water after which the barrel is taken off from the support.

As the portions composing the central distributing valve are accurately ground at 70 their faces and held in frictional contact with each other by the center-post and pressure-spring, the rotation of the machine is not interrupted nor is there any leakage during the rotation of the main-portion of 75 the valve. The action of the sprinkling machine is thereby made absolutely safe and the entire working of the machine rendered effective and reliable.

The improved distributing-valve can be 80 readily inserted in machines provided with the old-style of conical valves, so that the machines heretofore in use can be brought to a high degree of perfection and effectiveness.

Having thus described my invention, I claim as new and desire to secure by Letters Patent:

1. In a machine for sprinkling barrels, the combination of a rotary frame having 90 barrel-supports, supply-pipes extending to said barrel-supports, and a distributing valve to which said pipes are connected comprising a rotary main-portion having T-shaped channels leading to said pipes, means 95 to supply water to the upper branches of said channels for flushing out the barrels, and means for collecting the water which is drained off from the barrels by means of the lower branches of said T-shaped channels. 100

2. In a machine for sprinkling barrels, the combination of a distributing valve comprising a rotary main-portion provided with T-shaped channels, an upper portion provided with inlets for hot and cold water and coacting with said main-portion to alternately admit and cut off the hot and cold water to the upper branches of the T-shaped channels, a lower valve-portion having openings which are uncovered during the rotation of said main-portion and then communicate with the lower branches of said T-shaped channels, supply-pipes connected with the lateral branches of said channels, 115 and sprinkling pipes to which said supply-pipes are connected. 110

3. In a machine for sprinkling barrels, the combination of a distributing valve comprising a rotary main-portion provided with T-shaped channels, a stationary upper portion having segmental channels alternately brought into and out of register with the upper branches of said T-shaped channels, supply-pipes for hot and cold water connected with said upper portion and communicating with said segmental channels, a stationary lower portion having outlet-openings which register with the lower branches of said T-shaped channels when 120 125 130

the segmental channels are out of register therewith, supply-pipes connected with said rotary main-portion and communicating with the lateral branches of the T-shaped channels, and sprinkling pipes connected with said supply-pipes.

In testimony, that I claim the foregoing

as my invention, I have signed my name in presence of two subscribing witnesses.

JACOB MÜLLER, JR.
